UNITED STATES PATENT OFFICE.

JOSEPH P. HULDER, OF NEW YORK, N. Y., ASSIGNOR TO THE UNIT PLAYER ACTION CO., A CORPORATION OF NEW YORK.

PNEUMATIC ACTION FOR PLAYER PIANOS.

Application filed July 14, 1920. Serial No. 396,119.

To all whom it may concern:

Be it known that I, JOSEPH P. HULDER, a citizen of the United States, residing at the city of New York, county of Bronx, and 5 State of New York, have invented certain new and useful Improvements in Pneumatic Actions for Player Pianos, of which the following is a specification.

This invention relates to improvements in 10 action chests of pneumatic players for pianos or other musical instruments and particularly to the type of action chest having detachable valve boxes.

A player of the class to which the invention 15 relates has a series of striker pneumatics the operation of which is governed by a perforated note sheet traveling over a tracker bar having openings communicating with the valves that control the striker pneumatics.

In detachable valve actions heretofore devised it has been usual to couple an opening in the tracker bar with a port in the front of the valve box by means of a flexible tube connection. Consequently, when 25 it has been desired to remove the valve box, it has been necessary to disconnect the tube in addition to detaching the box. It will also be apparent that in assembling the action, or in replacing defective valves, considerable care must be used to correctly connect the valve boxes with the proper openings in the tracker bar.

One of the objects of my invention is to 35 overcome this objection by providing an action chest having passages for establishing communication with the tracker bar and whereby the valve boxes can be detached and replaced by merely unfastening or 40 fastening the means which hold the boxes in place.

A further object is to provide a detachable valve box containing two independent primary valves and communicating with a 45 single exhaust port in the action chest, which port is common to both valves.

Another object is to provide means for securing the valve boxes to the action chest, which means serve as guides for locating the 50 valve boxes in their proper places on the

action chest and permit of readily detaching the valve boxes, when desired.

Still further objects of the invention are to simplify the construction, to reduce the cost of manufacturing and assembling the 55 parts, and to increase the efficiency of the action chest.

In the accompanying drawings illustrating my invention,

Fig. 1 is a fragmentary plan view, partly 60 in section, of an action chest and attached valve boxes;

Fig. 2 is an elevation in section on the line 2—2 of Fig. 1;

Fig. 3 is an elevation in section on the 65 line 3—3 of Fig. 1;

Fig. 4 is an elevation in section on the line 4—4 of Fig. 1;

Fig. 5 is a front view of the action chest;

Fig. 6 is a rear view of a detached valve 70 box, and

Fig. 7 is a front view of a valve box attached to an action chest.

Referring to the drawings, 1 indicates an action chest having a series of valve boxes 75 2 detachably secured to the front wall thereof. A series of striker pneumatics 3, one for each note, are secured to the underside of the chest, with the hinged ends of the pneumatics extending forwardly beyond the 80 front wall of the chest. In practice, as is usual in player-pianos, the action chests will be arranged in tiers within the case, and disposed in front of the abstracts and above the key levers, with the valve boxes facing 85 towards the front of the piano or instrument.

The action chest has a lengthwise extending chamber 4 from which the air is exhausted in any suitable manner. The chamber is preferably covered with a piece of suitable 90 air-tight material 5, such as is generally used in making the striker pneumatics, which covering is glued over the entire upper surface of the chest. Formed through the solid front wall 6 of the chest is a series 95 of angular passages 7, preferably arranged in pairs, and providing communication between the valve boxes 2 and the interiors of the pneumatics 3. 8 are a series of horizontal pasages also formed through the wall 100

6 and communicating directly with the exhaust chamber 4, the passages 8 being preferably located between adjacent pairs of passages 7, as seen in Fig. 5, and being independent thereof.

Passages 9, which are provided for establishing communication between the valve boxes and the tracker bar (not shown), are formed clear through the solid lower wall 10 of the chest. The rear ends of the passages 9 are connected by tubes 10 with the openings in the tracker bar.

The valve boxes 2 are constructed with two separate compartments, each housing a valve 11 for controlling a striker pneumatic 15 3. The valves 11 are of the primary type well known in the art and require no further description. Each box 2 has passages or ports 12, 13, and 14 terminating in the 20 rear wall 15 thereof, and registering respectively with the ends of the passages 7, 8, and 9 in the front wall 6 of the chest. The mouth or opening of the exhaust passage 13 in the valve box is longer than that 25 of the corresponding passage 8 in the action chest, and the ends of said passage 13 terminate in vertical slots 16 which serve to connect the bleeds 17 with the exhaust chamber. The rear wall 15 of the valve box is 30 preferably lined with a suitable packing material to form an air-tight joint between the box and the adjacent wall of the action chest.

By referring to the drawings, it will be seen that each of the exhaust passages or 35 ports 8 is arranged to serve both of the two valves 11 contained in the valve box 2, the valves communicating with said port through the port 13 in the valve box. In other words, according to my invention the 40 exhaust port is common to the two valves contained in the valve box. This arrangement simplifies the construction of the chest and eliminates the necessity of providing separate exhaust ports for each valve.

The means for locating the valve boxes 45 comprise studs 20 projecting outwardly from the front face 6 of the action chest and passing through transverse openings 19 in the central portion of the valve boxes. When 50 the valve boxes are placed on the studs, the ports in said parts will come in proper registration. Nuts 18 screwing on the outer ends of the studs 20 and against the springs 21 serve to detachably and securely hold the 55 valve boxes in proper position.

Various modifications and changes may be made in the details of the invention as herein described, without departing from the scope of my invention as defined in the 60 claims.

What I claim is:

1. In a pneumatic player mechanism, an action chest, striker pneumatic supported on the underside of the chest, valve-boxes supported on the front of the chest, each con-

taining two independent pneumatic valves, said action chest having an interior exhaust chamber, passages through the front wall each forming a common passageway from the exhaust chamber to both valves of each 70 valve-box, separate passages in the front wall each connecting a valve with a corresponding striker pneumatic, and separate passages extending transversely through the bottom each connecting a valve with a tube 75 leading to the tracker bar.

2. In a pneumatic player mechanism, an action chest having an exhaust chamber, and a valve box detachably secured to the chest, said valve box containing two independent 80 valves both of which communicate with the exhaust chamber through a single common passage.

3. In a pneumatic player mechanism, an action chest, striker pneumatics secured to the underside of the chest and projecting beyond its front wall, valve-boxes detachably secured to the front wall each containing two independent pneumatic valves, said action chest having an interior exhaust chamber and an air-tight fabric cover, passages through its front wall each forming a common passageway from the exhaust chamber to both valves of each valve-box, separate 85 passages in its front wall each connecting a valve with a striker pneumatic, and separate 90 passages in its bottom each connecting a valve with a tube leading to the tracker bar.

4. In a pneumatic player mechanism, an action chest having an exhaust chamber and a passage leading from a face of the chest to said chamber, a valve box detachably secured to said face of the chest, said valve box having an exhaust passage opening in the face adjacent to the chest and in alignment with the passage in the chest, the ends of the exhaust passage opening in the face of the box terminating in slots connected with bleed ducts in said box.

5. In a pneumatic player mechanism an 110 action chest having an exhaust chamber, a series of striker pneumatics secured thereto, a series of valve boxes, each containing two independent primary valves both of which communicate with the exhaust chamber 115 through a common passage, and means for detachably securing the valve boxes to the action chest.

6. In a pneumatic player mechanism an 120 action chest, a series of striker pneumatics secured thereto, a valve box containing two independent primary valves and means for detachably securing the valve box to the chest comprising a stud projecting outwardly from the chest and passing through a transverse opening in the central portion of the valve box, a nut on the outer end of the stud and a spring between the nut and the valve box.

7. In a pneumatic player mechanism, an 130

action chest having an interior exhaust chamber, a series of striker pneumatics secured to the underside of the chest, a series of valve boxes each containing two independent primary valves detachably secured to the front wall of the chest, a series of independent passages in the front wall of the chest leading from the valve boxes to the exhaust chamber and the pneumatics respectively, and a series of passages in the lower wall of the chest each leading from a valve box to a tracker bar connection.

JOSEPH P. HULDER.
